UNITED STATES PATENT OFFICE.

HARMON W. CORNELL, OF OWEGO, NEW YORK.

CORN-SHELLER.

SPECIFICATION forming part of Reissued Letters Patent No. 9,882, dated September 27, 1881.

Original No. 233,733, dated October 26, 1880. Application for reissue filed April 16, 1881.

To all whom it may concern:

Be it known that I, HARMON W. CORNELL, of Owego, in the county of Tioga and State of New York, have invented certain new and useful Improvements in Corn-Shellers; and I do hereby declare that the following is a full, clear, and exact description thereof, reference being had to the accompanying drawings, and to letters of reference marked thereon, which form 5 a part of this specification.

This invention relates to certain improvements in corn-shellers of that class having a series of concentric circles of projecting teeth and a revolving wheel having a beveled rim 15 with teeth or corrugations; and it consists in the peculiar arrangement of the parts, whereby the entire surface of the revolving disk is utilized for shelling purposes.

It also consists in a guard, in combination 20 with the other parts, for holding the ear of corn to the disk below its center, all as herein-after more fully set forth.

In order to enable others skilled in the art to which my invention appertains to make and 25 use the same, I will now proceed to describe its construction and operation, referring to the annexed drawings, in which—

Figure 1 is a longitudinal vertical section of a corn-sheller embodying my invention, and 30 Fig. 2 is a vertical cross-section of the same.

A represents the frame-work of my corn-sheller, provided in the lower portion with the usual separator, B, to separate all the chaff, &c., from the shelled corn. This separator may 35 be operated in any suitable manner from the gearing of the machine.

Within the frame-work A is a circular disk, D, secured upon the end of the shaft C, and this disk is, upon its inner face, provided with 40 teeth a, which are arranged in a series of concentric circles, as shown.

The letter F indicates a wheel secured upon a shaft, G, and having its rim beveled or inclined toward the disk D, and upon this rim 45 are a series of equidistant ribs or elongated teeth, b.

In the angle between the wheel F and disk D works the angular presser-bar H, having a spring, I, connected to its upper arm, and the

tension of this spring is regulated by means 50 of a slotted plate, d.

In corn-shellers of this class the disk D is generally placed upon a shaft which runs across the frame and has a bearing on each side of the disk, and in such construction the wheel 55 F must be set sufficiently far back to allow the cobs to pass down below the shaft, and hence a great portion of the disk is lost for shelling purposes, so that to get a proper length of shell-ing-surface it is necessary to make the disk 60 very large.

In my invention the disk is secured on the end of the shaft, leaving the space in front perfectly clear; and by reason of this construction I am enabled to set the shaft G so close 65 to the disk D that the wheel F will have its larger periphery opposite, or nearly opposite, to the center of the disk, and hence the entire surface of the disk from the center to the circumference is utilized for shelling purposes. 70 As a consequence the disk and wheel may be made of less size, and yet have the same amount of shell-ing-surface.

The two shafts C and G are connected and rotated by means of suitable gearing, substantially in the manner shown, or in any other convenient manner that will make them run at different speeds, as the wheel F must be run faster than the disk D. The shaft C, which carries the disk D, must also be more or less elevated—75 say from one-fourth to three-fourths of an inch—above the shaft G, so as to give the desired draft for running the ears of corn through the machine. The draft may be changed as desired by putting thicker or thinner washers or 80 plates under the box or bearing for the shaft C, or by babbetting the box.

The letter L indicates a guard attached to the end of the frame, and extending in front of the disk opposite the wheel F and below the 90 center of the disk, so as to hold the cobs in position and against the wheel after they pass from under the presser-bar.

Having thus fully described my invention, what I claim as new, and desire to secure by 95 Letters Patent, is—

1. In combination with the toothed disk D, mounted on the end of the shaft C, and the

wheel F, mounted on the shaft G, and extending across the face of the disk from its periphery to its center, the yielding presser-bar H, extending between the wheel and disk, substantially as specified.

5. 2. In combination with the toothed disk D, mounted on the end of the shaft C, and the wheel F, mounted on the shaft G, and extending across the face of the disk from its periphery to its center, the presser-bar H and guard

L, adapted to feed and guide the ear from the periphery to the center of the disk, substantially as specified.

In testimony that I claim the foregoing I have hereunto set my hand this 21st day of 15 March, 1881.

HARMON W. CORNELL.
